UNITED STATES PATENT OFFICE.

FRANK J. BALLINTINE, OF KANSAS CITY, MISSOURI, ASSIGNOR TO PARKER-WASHINGTON COMPANY, OF KANSAS CITY, MISSOURI, A CORPORATION OF WEST VIRGINIA.

MACHINE FOR HEATING SURFACES.

1,007,173.

Specification of Letters Patent. Patented Oct. 31, 1911.

Application filed August 14, 1909. Serial No. 512,804.

To all whom it may concern:

Be it known that I, FRANK J. BALLINTINE, a citizen of the United States, and resident of Kansas City, Missouri, have invented certain new and useful Improvements in Machines for Heating Surfaces, of which the following is a specification containing a full, clear, and exact description, reference being had to the accompanying drawings, forming a part hereof.

My invention relates to improvements in machines for heating surfaces, the object of my invention being generally to improve the construction of the combustion chamber, blower and the means for elevating the hood in machines of this class, thereby reducing to a minimum the weight of the heating apparatus and increasing the efficiency of the burners with a minimum amount of liquid fuel.

For the above purposes my invention consists in certain novel features of construction and arrangement of parts as will be hereinafter more fully set forth, pointed out in my claims and illustrated in the accompanying drawings, in which:

Figure 1 is an elevation of the complete machine; Fig. 2 is a rear elevation of the hood, combustion chamber and means for elevating the hood showing the relative position of the blower and combustion chamber, a portion of the machine frame being shown in section; Fig. 3 is a vertical sectional elevation through the hood and combustion chamber with a portion of the blower casing being broken away to illustrate the position of the burner therein; and, Fig. 4 is a sectional plan taken on the line 4—4 of Fig. 3.

Referring by numerals to the accompanying drawings: 1 designates the machine frame. For convenience in operating the machine the frame is mounted upon the wheels 2 and 3, the former of which are arranged to be driven by an engine such as 4.

5 designates a steam generator supported in the machine frame and designed to supply steam to the engine 4.

6 designates a blower casing supported by the standards 7 which are secured to the machine frame adjacent the rear end of the frame. Mounted in the walls of the casing 6 is a shaft 8 having on its one end a pulley 9. An engine such as 10 is supported by the machine frame adjacent the blower cas-

ing 6 and is connected with the pulley 9 by the belt 11. This engine is designed to be supplied with steam from the steam generator 5 by any suitable connections (not shown). Blades (not shown) are supported upon the shaft 8 and arranged to rotate within the casing 6. A truncated cone-shaped combustion chamber 12 is connected with the casing 6 and supported from the machine frame by the hangers 13. A perforated baffle-plate 14 is secured within the combustion chamber adjacent its lower end and the entire combustion chamber is lined with asbestos 15, fire brick or the like. A burner tube 16 is inserted through the blower casing and projects downwardly therethrough and terminates within the combustion chamber. A valve 17 is connected with the burner tube 16 and is arranged to be supplied with steam and hydro carbon under pressure through the pipes 18 and 19. Located in the pipe 18, adjacent the valve 17, is a valve 20 to control the steam entering the burner tube. A similar valve 21 is located in the pipe 19 to control the passage of oil under pressure to the burner. By this arrangement of burners I am enabled, by manipulating the valves 20 and 21, to regulate to a nicety the amount of steam or oil to the burner, and, by manipulation of the valve 17, I am enabled to control the combined oil and steam entering the burner tube.

A hood 22, has a reduced neck portion 23, which neck portion, embraces the lower end of the combustion chamber 12. Stubs 24 are fastened to the neck portion 23 of the hood 22 and the free ends of an inverted U-shaped hanger 25 are secured to said stubs. Braces 26 are secured to the hood at one end and at their other end to the stubs, and said U-shaped hanger embraces and is secured to the stubs by means of the nuts 27. A piston rod 28 is fixed to the upper end of the hanger 25 and projects into a cylinder 29 wherein a fluid, under pressure, acts on a piston (not shown) connected to the rod 28 and elevates the hood 22.

While I have shown my apparatus mounted upon a wheeled truck and have illustrated an engine for moving the truck and have shown a blower designed to be driven by an engine mounted on the machine frame and have illustrated and described a U-shaped hanger for the hood, which hanger

is operated by a piston and a cylinder in which air or steam is injected and have further illustrated a conical combustion chamber, I do not desire to be understood as limiting myself to the use of this specific construction of these parts.

In the practical operation of the device the machine is positioned at a point upon an asphalt paving where it is desired to make a repair and the hood lowered into engagement with the pavement. The oil and steam valves of the burner are then opened and adjusted to a proper mixture of oil and steam to create a perfect combustion of oil and steam and the oil issuing from the burner tube 16 is then ignited. It is obvious that by reason of the employment of a single burner too great a heat might be discharged upon a limited area of paving, and, to provide a means for breaking up and distributing this flame I have provided a baffle plate which is fixed adjacent the lower end of the combustion chamber through which plate the flame is discharged in a number of small jets. After the burner is ignited and the valves regulated to the proper adjustment for a perfect combustion, the engine 10 is set in motion and the blades of the fan within the casing 6 are rotated, thus causing a blast of air to discharge directly into the combustion chamber. By this arrangement of burner tube, blower, combustion chamber and baffle plate I am enabled to attain the maximum amount of heat in a minimum of time consuming a minimum amount of fuel.

Heretofore the surface-heating devices of this class have employed cumbersome and extremely heavy constructions of combustion chambers which necessitated the construction of extremely large and heavy truck frames. By the construction shown, I have reduced not only the weight of the combustion chamber but have reduced to a minimum the number of parts employed in such a machine.

I claim:

1. In a machine for heating surfaces, a frame, a vertically disposed combustion chamber carried by said frame, a hood provided with a neck mounted over the lower end of said combustion chamber, a fan blower casing connected with the opposite end of the combustion chamber, a vertically disposed burner projecting into the upper end of said combustion chamber, a fan mounted in said fan blower casing above the discharge end of the burner, and a horizontally disposed baffle plate located in the combustion chamber between the hood and fan blower and beneath the discharge end of the burner.

2. In a machine for heating surfaces, a frame, a vertically disposed combustion chamber carried by said frame, a hood hav-

ing a collar arranged around the lower end of the combustion chamber, a vertically disposed burner located in the upper end of the combustion chamber, a fan casing carried by the combustion chamber and in communication therewith above the burner, a fan blower mounted in said fan casing above the discharge end of the burner and discharging into the upper end of the combustion chamber, whereby the products of combustion generated in the combustion chamber are blown downwardly through the combustion chamber into the hood.

3. In a machine for heating surfaces, a frame, a vertically disposed combustion chamber carried by the frame, a hood positioned on the lower end of the combustion chamber, a baffle plate positioned in the lower end of the combustion chamber, a burner positioned in the upper end of the combustion chamber and above the baffle plate, a fan casing carried by the upper end of the combustion chamber and in communication therewith above the burner, a fan blower mounted in said casing whereby the products of combustion and hot gases generated in the combustion chamber are forced downwardly through the combustion chamber onto the surface to be heated.

4. In a machine for heating surfaces, a hood, means for lowering and elevating the hood, a vertically disposed combustion chamber discharging into the upper end of the hood, a horizontally disposed baffle plate mounted in the combustion chamber, an oil burner mounted in the upper end of said combustion chamber above the baffle plate, a fan casing in communication with the combustion chamber above the burner, a fan blower mounted in said casing whereby the products of combustion generated in the combustion chamber and the hot gases of the combustion chamber are blown downwardly through the combustion chamber into the hood.

5. In a machine for heating surfaces, a frame, a vertically disposed combustion chamber carried by the frame, a hood suspended below and beneath said combustion chamber, means for elevating and lowering the hood, a burner arranged in the upper end of the combustion chamber, a fan casing in communication with the combustion chamber above the burner, a fan blower mounted in said casing and above the burner discharging downwardly through the combustion chamber and affording a direct blast for the burner and blowing the hot gases generated in the combustion chamber downwardly through the lower end of the combustion chamber and into the hood, and an engine for operating said fan blower.

6. In a machine for heating surfaces, a frame, a vertically disposed combustion chamber carried by the frame, a hood, means

for elevating and lowering the hood, a horizontally disposed baffle plate located in the lower end of the combustion chamber, a fuel burner mounted in the upper end of the combustion chamber and adapted to discharge its flame downwardly into the combustion chamber, a fan blower casing in communication with the combustion chamber above the fuel burner, a fan blower mounted in said casing above the upper end of the combustion chamber and above the fuel burner, an engine for operating the fan blower whereby its blast is imparted directly downwardly to the flame of the fuel burner and the hot gases

in the combustion chamber and impelling 15 flame and hot gases of combustion downwardly and blowing the hot gases out of the lower end of the combustion chamber and into the hood and onto the surface to be heated and away from the fan blower mechanism. 20

In testimony whereof, I have signed my name to this specification, in presence of two subscribing witnesses.

FRANK J. BALLINTINE.
